UNITED STATES PATENT OFFICE.

JOHN W. SMITH, OF CHICAGO, ILLINOIS, ASSIGNOR TO HOWARD SMALL AND CHARLES A. DUREN, BOTH OF PHILADELPHIA, PENNSYLVANIA.

VACUUM-CLEANER.

1,077,102.

Specification of Letters Patent.

Patented Oct. 28, 1913.

Continuation of application Serial No. 573,599, filed July 25, 1910. This application filed April 22, 1912.
Serial No. 692,486.

To all whom it may concern:

Be it known that I, JOHN W. SMITH, a citizen of the United States, residing at Chicago, in the county of Cook and State of Illinois, have invented certain new and useful Improvements in Vacuum-Cleaners, of which the following is a specification.

The invention relates to vacuum cleaners, and more especially to the mounting of the pumping unit for the vacuum chamber.

An object of the invention is to provide means for supporting the pumping unit, whereby the same is yieldingly supported from the outer casing of the vacuum cleaner, so as to prevent the transmission of sound from the operating mechanism of the pump to the outer casing, and hence to the exterior of the vacuum cleaning apparatus.

Referring to the drawings,—Figure I is a transverse sectional view through the center of a vacuum cleaner involving my invention, the pumping mechanism and its associate parts, however, being shown partly in elevation; Fig. II is a fragmentary vertical section through the device on a plane at right angles to that of Fig. I; Fig. III is a similar view of a modification; and Fig. IV is a detail of a further modification.

In the drawings, the casing is designated by the numeral 1 and is double-walled for the purpose of deadening the sound caused by the operation of the device. The casing is mounted on a platform 2 supported by rollers 3. The pumping mechanism is supported from the wall of the casing by means of an annulus 4 riveted to the wall and rabbed as at 5 for the reception of a packing 6.

Upon the packing rests an annulus 9, between which and a ring 10 is secured the diaphragm 11 of leather or other flexible material, which supports the pumping mechanism. Screws 12 and nuts 13 secure the annuli 9 and 10 and 4 together, and when the nuts are removed the screws are held in position in the lower annulus by cotter-pins 14.

The pump is of the diaphragm type and includes a pumping chamber 15, having inlet valves 16, which in the type shown, consist in strips of thin flexible material, as for example, sheet metal, secured at their ends and free to bow in either direction, the valve seats being slightly concave longitudinally to

permit of the bowing of the valves. In Fig. I the position of the valves when closed is shown in full and when open in dotted lines.

The diaphragm before described extends into the pumping chamber, the casing whereof is composed of two members 17, 18, secured together by screws 19 with the diaphragm between their adjacent edges. The diaphragm is given a pulsating movement by a disk member 20 between the edges of which and a ring 21 the diaphragm is clamped by means of screws 22. At its center the disk 20 is provided with a number of elongated narrow valve seats 23, which are covered by valves 24 similar in all respects to the valves 16 above referred to. The disk 20 is given its reciprocating motion through a pair of arms 25 rigidly secured at diametrically opposite portions of the periphery thereof and formed at their lower ends with collars 26 which embrace eccentrics 27 mounted on the armature shaft 28 of a motor 29. Ball bearings 30 are provided between the arms and the eccentrics. 32, 32, are counterbalances secured to the armature shaft by clamping bolts 33, 33. The motor 30 is supported from the pump casing, the latter being provided with perforated lugs 34, with which screws 35, extending through ears 36 in the motor casing, engage. The motor shaft is also provided with supporting roller bearings 37, one of which is illustrated in Fig. I in section. Upon the upper end of the pump casing is mounted a perforated plate 38, the purpose of which is to keep the fabric of the straining bag, to be described later, away from the valve and the seats. A handle 39 serves as a convenient means for removing and handling the pump and motor, when for any reason it is desired to remove them from the cleaner casing. In Fig. III I have shown a modification of the manner of mounting the pump. In this case, the operating diaphragm of the pump 11' is not extended beyond the casing at all, but the pumping mechanism is supported from another independent diaphragm 40. The latter is annular in form, and is clamped at its inner periphery between the plate 38' and the pump casing at 41.

In order to avoid unnecessary wear upon the diaphragm, the edge of the pump casing

against which the diaphragm bears is chamfered, and the edge of the plate 38' is dished upwardly. The outer periphery of the diaphragm 40 is clamped between two dished 5 rings 42 and 43, by means of screws 44. The lower of these rings 43 is formed integral with a short cylinder 45, which rests upon a packing 6' received within a rabbet in the collar 4'. The latter is riveted to the 10 walls of the vacuum vessel. Screw bolts 46 with nuts 47 clamp the rings 42, 43, and the cylinder 44 firmly against the packing 6'. The vacuum casing is provided with a cover 48 having a handle 49 and an opening 15 50 for connection with a suitable hose. Between the cover and the upper edge of the casing is an annular part 51 having an internal groove 52, within which is seated the edge 53 of a dished perforated plate 54. 20 The latter element is formed with a circumferential groove 55, within which is clamped the upper edge of a fabric bag or receptacle 56, by means of a ring 57. Pivoted clamping bolts 58 with thumb nuts 59, 25 serve to clamp the cover upon the casing.

In the modification shown in Fig. IV, the diaphragm 60 connecting the pump chamber and casing is shown as of metal corrugated to give the necessary flexibility 30 to deaden the sound. In this form, the pump diaphragm may be made of a different material, and both diaphragms are clamped together between the edges of the pump casing, as plainly shown in Fig. IV.

35 It is obvious that the form of the metal diaphragm may vary widely, and the pump chamber may depend below the annulus 4 instead of being supported above it, as shown in Fig. IV, but such modification will 40 clearly be within the scope of my invention. In my improved vacuum cleaner as described above, the casing is divided into two chambers, a suction and a pressure chamber, by the pump and the diaphragm connecting it to the wall of the casing, communication between the two chambers existing only through the pump, and but a single 45 packing 6 being necessary to effect the complete isolation of the chamber. It is not 50 the purpose of this connection to dispense with and obviate the noise incident to the suction and expulsion of air, for the casing with its sound-deadening walls has proven sufficient for this purpose, but my present 55 invention is intended to take care of and prevent the noise due to the movements of the operative parts. As described above, the pump and motor are connected to the casing only by the flexible diaphragm which 60 does not readily transmit sound. There is, therefore, no continuous noise-conducting connection between the operating parts and the casing, such as exists when the connections are rigid, and even to a large extent when they include the packing usually 65

employed between the pump chamber and casing, and which is necessarily more or less compacted in adjusting the parts, and by the jarring incident to the operation of the machine.

Having thus described my invention, what I claim as new and desire to secure by Letters Patent, is:—

1. The combination of a casing having a vacuum chamber, a pumping unit for said vacuum chamber, a flexible diaphragm, means for connecting said flexible diaphragm to said casing, and means for connecting said diaphragm to said pumping unit, whereby said pumping unit is yieldingly supported by said casing. 70

2. The combination of a casing having a vacuum chamber, a pumping unit for said vacuum chamber, including a vibrating member, and means for vibrating said member, a flexible diaphragm, means for connecting said flexible diaphragm to said pumping unit, and means for connecting said flexible diaphragm to said casing, whereby said pumping unit is yieldingly supported within said casing. 85

3. The combination of a casing, a diaphragm pump within the same, the diaphragm of the pump extending beyond the pump cylinder and connected to the casing 95 to form a support for the pump.

4. The combination of a support including an annulus, a diaphragm pump, the diaphragm of which extends outside the pump chamber and is connected to the said annulus. 100

5. The combination of a casing, a pump and motor supported within the casing, a flexible diaphragm connecting the pump and casing and together with the pump dividing 105 the casing into two chambers.

6. The combination of a casing having an internal shoulder thereon, a packing on the shoulder, an annulus clamped to the packing, a pump within the casing, and a flexible 110 diaphragm connecting the pump casing to the annulus.

7. The combination of a casing having an internal shoulder, an annulus resting upon said shoulder, a diaphragm pump, the diaphragm of which extends beyond the pumping chamber and is secured to the annulus. 115

8. The combination of an outer casing, a pump chamber, a diaphragm within said pump chamber, means for reciprocating said diaphragm, said means being supported by the pump chamber, and a flexible diaphragm for connecting the pump chamber to the outer casing for supporting the same. 120

9. The combination of an outer casing, a diaphragm extending across said outer casing and attached thereto, whereby said casing is divided into two chambers, a pump chamber mounted on said diaphragm, said pump chamber being spaced from said outer 125 130

casing, whereby the same is yieldingly supported, a rigid member connected to said diaphragm within the pump chamber, and means connected with the rigid member for reciprocating the same, said means being supported by the pump chamber.

In testimony whereof, I have hereunto

signed my name at Chicago, in the county of Cook, and State of Illinois this 8th day of April 1912.

JOHN W. SMITH.
